UNITED STATES PATENT OFFICE.

CHARLES A. ROLFE, OF ROCHESTER, NEW YORK, ASSIGNOR TO ROLFE ELECTRIC COMPANY,
OF ROCHESTER, NEW YORK, A CORPORATION OF NEW YORK.

ELECTRICAL-CIRCUIT PROTECTOR.

No. 867,212.

Specification of Letters Patent.

Patented Sept. 24, 1907.

Application filed September 18, 1905. Serial No. 279,003.

To all whom it may concern:

Be it known that I, CHARLES A. ROLFE, a citizen of the United States, residing at Rochester, in the State of New York, have invented a certain new and useful 5 Improvement in Electrical-Circuit Protectors, of which the following is a full, clear, concise, and exact description, reference being had to the accompanying drawings, forming a part of this specification.

My invention relates to electrical circuit protectors 10 for protecting electrical circuits and instruments from unduly strong currents.

Prominent objects of the invention are: to provide a simple, practical and inexpensive form of circuit protector, and to simplify the construction thereof, and 15 thereby minimize expense; to reduce the amount of space required for the protectors when mounted in bank; to increase the efficiency and effectiveness of such devices, and to accomplish the foregoing and other desirable results in a simple and expeditious manner.

20 In the arrangement which I show herein for carrying out my invention, a set or series of protectors are mounted upon a support or board on opposite sides thereof. Each protector conveniently consists of a removable cartridge containing a self-soldering protective mechanism which is operated by the passage of an unduly strong current. This cartridge is mounted in suitable contacts which are so arranged that as a preferred arrangement, the cartridge is in vertical position. When an unduly strong current operates the cartridge, 25 the circuit is opened within it, and suitable ground and alarm circuits are preferably closed by additional contacts. By providing the cartridge with an entire circuit opening mechanism, long external springs such as have heretofore been used to coöperate with heat cartridges in electrical circuit protectors, are dispensed with. All that is necessary are suitable contacts to support and connect with the cartridge, but these need not be of spring construction, and therefore, are much 30 more cheaply constructed and more easily handled.

35 By mounting the cartridge in a vertical instead of a horizontal position the amount of space required by each protector is less, and the whole arrangement is more compact and smaller in size, so that space is much better economized.

40 In the accompanying drawings, Figure 1 is a cross sectional view of a board or rack provided with a bank of protectors embodying my present invention. Fig. 2 is a side view of a portion of the same. Fig. 3 is a longitudinal section of the cartridge; and Fig. 4 is a view 45 of a detail construction.

In the drawings I have shown a part of a protector board provided with a set or bank of protectors; the board has a support or frame piece 1, on the opposite sides of which the protectors are mounted. These

protectors are conveniently arranged in rows with various protectors in each row opposite one another. As the protectors are alike in construction, a description of one of them will serve for all: Each protector comprises a heat cartridge 2, supported by contacts 3 and 4. The heat cartridge 2, conveniently consists of a tube 5, of insulating material containing a shuttle-like structure 6, made in the form of semi-cylindrical shell 7, with end lugs or disks 8, 8 which are fitted within and close the opposite ends of the tube or barrel 5. One of the disks 8, supports a plug consisting as shown in 60 Fig. 4, of an insulating cylinder 9, provided at one end with a metallic cap 10, and at the other end with a metal sleeve 11, having forks 12, 12. A rotary toothed wheel 13 is pivoted at 14, and soldered between the forks 12, 12. A coil 15, of fine wire, is wound around 70 the sleeve 11. One end of this coil 15, is connected with the cap 10, and the other end with one of the forks 12, 12. The other disk 8 of the cartridge, supports a sliding plunger 16, which is arranged to slide relatively to said disk 8. This plunger 16 is provided with a 75 spring clip or catch 17, the end of which is adapted and arranged to engage the teeth of the wheel 13. A spring 18, is arranged outside of the inner reduced end of the plunger 16, and braced against a middle or intermediate disk 19, formed on the shell 7. The end of the 80 plunger 16, is desirably provided with a flat disk 20.

The contacts 3 and 4, upon which the cartridge 2 is mounted, are provided by metallic strips 22 and 21 respectively, which extend vertically alongside of a board or support 1, and have their ends bent outwardly 85 to form such contacts. Other metallic strips 23 and 24, are arranged between the strip 21 and the board 1. The upper end of the strip 23 is also bent outwardly, so that its bent end 25, comes above the plunger 16 of the heat cartridge when the latter is in position in 90 its contacts 3 and 4. The other strip 24, extends up and makes connection with lightning arrester carbons 26, mounted upon the top of the board 1.

The strips 21, 22, 23 and 24 are secured to the support 1 by screws 27 and 28, which extend through 95 such strips into the support 1. Insulating sleeves 29 and 30 are arranged outside of these screws 27 and 28, and insulating strips 31, 31 interposed between the successive strips; thus the strips are all insulated from one another and from the support 1. The lower end of the strip 22 of each right hand protector, is turned outwardly so as to form a switch board terminal 32, and an additional strip 33 is arranged between support 1 and the strip 24, and supported and insulated the same as the other strips, and has its lower end turned outwardly so as to form the other switch board terminal 34. In the left hand protectors, the strip 21 is extended downwardly, then bent outwardly, so as to form the line terminal 35.

The innermost strip 33, is also extended down and out so as to form the other line terminal 36.

A connector 37, is extended between the lower end of the strip 21 of each right hand protector and the strip 24 of the corresponding left hand protector. Another connector 38, extends between the strips 33 and 22 of oppositely disposed protectors. The strips 21 and 24 of each protector, are connected with each other. Thus the circuit is made from one line to terminal 35, thence to strip 21 of left hand protector, then through the heat coil 2 of such protector, strip 22, conductor 38, strip 33 of right hand protector, terminal 34 to switchboard; thence back to terminal 32, to strip 22 of right hand protector, heat coil 2 thereof, strip 21, conductor 37, left-hand strip 33 and terminal 36 to line. The lightning arrester connections are made between strips 21 and 24. Strips 23, 23 are extended down and provided with terminals 41, 41, to which an alarm circuit is connected. Thus in the operation of the 20 protector if either protector operates, alarm circuit is closed by the plunger 16 striking one of the extensions 25.

A cross bar 42, is secured by screwing it into and through the support 1, above the two protectors forming a pair; upon the operation of either protector, this strip 25 will strike the bar 42, and thereby ground the circuit as well as opening it in the protector, and closing the alarm circuit through contact 25.

The particular form of the heat coil 2 shown herein 30 has been illustrated, described and claimed in another application Serial No. 277,948, filed September 11, 1905, and therefore is not claimed alone in this application.

It will be understood that changes and modifications can be made without departing from the spirit of my invention.

What I claim is:

1. The combination with a board or support, of line contacts running lengthwise of the same and having their ends bent, a heat cartridge supported by said line contacts lengthwise of said board or support, said heat cartridge being provided with a sliding member, and a contact strip also running lengthwise of said board and having its end bent so as to come opposite the end of said sliding member, whereby the latter upon operation makes connection with said strip.

2. The combination with a board or support, of line contacts running lengthwise of the same and having their ends bent, a heat cartridge supported by said line contacts lengthwise of said board or support, said heat cartridge being provided with a sliding member, a contact strip also running lengthwise of said board and having its end bent so as to come opposite the end of said sliding member, whereby the latter upon operation makes connection with said strip, and a ground contact on the other side of the bent end of said contact strip, with which the latter is adapted to make connection when actuated by said plunger.

3. The combination with a board or support, of line contacts running lengthwise of the same and having their

ends bent, a heat cartridge supported by said line contacts lengthwise of said board or support, said heat cartridge being provided with a sliding member, a contact strip also running lengthwise of said board and having its end bent so as to come opposite the end of said sliding member, whereby the latter upon operation makes connection with said strip, a ground contact on the other side of the bent end of said contact strip, with which the latter is adapted to make connection, when actuated by said plunger, lightning arrester electrodes 26, 26 supported upon said board or support, and contact strips 24, 24 for said electrodes.

4. The combination with a supporting board, of metallic strips secured to said board alongside of the same, there being four strips, three of which have their ends bent outwardly, and the fourth of which, extends upwardly beyond the others, a heat cartridge supported by two of the outwardly bent ends of two of said strips; said cartridge being provided with a circuit opening device and means for actuating the same, and having a part which projects outwardly upon operation, so as to engage the outwardly bent end of the third of said bent strips, and a lightning arrester with which the fourth strip makes connection.

5. The combination with a vertically disposed support, of heat cartridges arranged on opposite sides thereof, each of such cartridges being provided with circuit controlling mechanism, and the means for actuating the same, metallic strips arranged on opposite sides of said support, there being four strips on each side, three of which having their ends bent outwardly, the heat cartridge being supported by two of the same, and the third being extended over the end of the cartridge, a cross bar 42 arranged above the bent ends of the third mentioned metallic strips, and a lightning arrester mounted upon the support, the 95 fourth strip on each side of the board being connected with said lightning arrester.

6. The combination with a pair of metallic supporting strips, of a heat cartridge supported thereby, said cartridge being provided with self-soldering circuit-opening mechanism, and having means extending through the cartridge for returning said mechanism to normal position.

7. The combination of a pair of metallic supporting strips and a heat cartridge supported thereby, said cartridge being provided with self-soldering circuit-opening mechanism, and having a reciprocating plunger operated by said mechanism and extended through the cartridge, whereby it can be actuated to return said mechanism to operative position.

8. The combination with a pair of supporting strips, of a heat cartridge supported thereby, said cartridge being provided with circuit-controlling mechanism and having a movable part extended through said cartridge, and a third strip arranged to be contacted with said movable part.

9. The combination of a pair of metallic supporting strips, a heat cartridge supported thereby and provided with self-soldering circuit-opening mechanism, having a plunger releasable by said mechanism upon operation, said plunger extending through one end of the cartridge, and a third strip arranged opposite said plunger so as to be contacted with by the same upon release.

In witness whereof, I hereunto subscribe my name this 13th day of September A. D. 1905.

CHARLES A. ROLFE.
